UNITED STATES PATENT OFFICE

2,637,300

AIR HAMMER CONSTRUCTION

Paul R. Van Sittert, Shaker Heights, Ohio, assignor to The Rotor Tool Company, a corporation of Ohio.

Application March 10, 1950, Serial No. 148,990

3 Claims. (Cl. 121—19)

1

This invention relates to automatic directional valving for a reciprocating fluid driven tool.

An object of this invention is to provide a tool having a maximum cylinder bore length.

Another object of this invention is to provide a pressure responsive fluid directing valve having flat surface contact valving parts.

A still further object of this invention is to provide an annular valve adapted to constitute a portion of the cylinder bore of a fluid motor, the valve having flat valving surfaces easily replaceable in the event of damage or wear.

Other objects and a fuller understanding of the invention may be had by referring to the following description and claims, taken in conjunction with the accompanying drawings, in which:

Figure 1 is a longitudinal sectional view of a pneumatic hammer employing the principles of this invention, the section being taken along line 1—1 of Figure 3 and illustrates the piston in the striking position and the valving parts moved to direct air to return the piston;

Figure 2 is a section similar to Figure 1 and illustrates the piston in its endwise work stroke with the valving parts positioned to drive the piston in its work stroke;

Figure 3 is a sectional view along the line 3—3 of Figure 1;

Figure 4 is a top view of the valve cap;

Figure 5 is a sectional view along the line 5—5 of Figure 4;

Figure 6 is a bottom view of the valve cap;

Figure 7 is a top view of the valve body;

Figure 8 is a sectional view along the line 8—8 of Figure 7;

Figure 9 is a bottom view of the valve body;

Figure 10 is a top view of the ring valve; and

Figure 11 is a sectional view along the line 11—11 of Figure 10.

The tool chosen to illustrate the principles of this invention is a pneumatic chipping hammer having a tool body 10 with a longitudinal bore 11. A handle 12 having a hand grip portion 13 and a cap portion 14 is threadably secured to the end of the body 10. An air line 15 is adapted to supply the motive fluid to the tool to reciprocably drive a piston 16 within the bore 11. For the purposes of illustrating this tool, a tool bit 17 is illustrated as the implement being hammered by the piston 16. A bushing 18 is mounted in the end of the body 10 to hold the tool bit 17. Air conduits 19, one of which is in view in Figures 1 and 2, extend longitudinally within the body 10 and serve to deliver air to the end of the bore 11 near the tool bit 17. An air exhaust 20 is pro-

2

vided at a position between the ends of the bore 11 to allow the motive fluid to escape from the bore 11.

An improved directing valve 21 is positioned at the end of the bore 11 opposite from the tool bit 17 and is held in place by the cap portion 14 of the handle 12, as illustrated in the Figures 1 and 2. The directing valve 21 is annular in this embodiment and has an internal bore 27 of the same diameter as the bore 11. The bore 27 forms a continuation of the bore 11, and the combined lengths of the bores 11 and 27 define a tool cylinder 28. The piston 16 is adapted to reciprocate in the tool cylinder 28 employing both the bore 11 and the bore 27. Therefore, the first advantage of the directing valve 21 becomes apparent. The directing valve 21 serves as a useful portion of the tool cylinder and, therefore, adds nothing to the over-all length and weight of the tool in which it is employed. Consequently, a tool employing this valve may be shorter and lighter for a given power rating than a tool having conventional valves mounted on the end of the tool. By the same token, a tool employing this directing valve 21 will be more powerful for a given length.

The directing valve 21 has an external diameter less than the internal diameter of the cap portion 14 in order to define a distributing chamber 22 completely around the external diameter of the valve 21. Thus, the motive fluid may be delivered by the air line 15 into the distributing chamber 22 surrounding the valve 21. The valve 21 then serves to direct the motive fluid to drive the piston 16.

Referring to Figures 5 and 8, the directing valve 21 preferably comprises a valve body 23 and a valve cap 25 in this embodiment. An annular groove 24 in the valve body 23 and a flat wall surface 29 on the valve cap 25 cooperate to define a valve chamber 26, as indicated in the Figures 1 and 2. The annular groove 24 is provided with a flat wall bottom surface 30. The combination of the valve body 23 and the valve cap 25 is preferably spoken of as a valve cage. A sleeve 38 serves to assure correct alignment of the body 23 and the cap 25, and provides a smooth internal bore 27 to match the internal bore 11. A ring valve 35 is provided to reside within the valve chamber 26. The ring valve 35 has a flat surface 36 and a flat surface 37 and is dimensioned to fit freely in the valve chamber 26 in order that it may be moved in tight contact with the flat wall 29 or the flat wall 30.

The valve cap 25 is provided with at least one

air entrance 31, as best illustrated in Figure 5, but preferably has a plurality of air entrances 31 as illustrated in Figure 4. Thus, the volume of air which may enter into the valve chamber 26 may be relatively large without the necessity of providing one large entrance. In other words, the plurality of air entrances 31 may be spoken of as an air fluid entrance or fluid entrance means, it being understood that the number of entrances are multiplied strictly for design purposes. The cap 25 is also provided with an air exit 33 as illustrated in the Figure 5, or more properly, with air exit means. See Figure 4. Therefore, air entrance 31, the chamber 26, and the air exit 33 define a fluid passage from the distributing chamber 22 to the end of the tool cylinder 28. This passage may be followed by the arrows in Figure 2.

The valve body 23 is also provided with at least one air entrance 32, as illustrated in Figure 8, but preferably with a plurality of entrances, as illustrated in Figure 7. As discussed in connection with air entrances 31, the air entrances 32 may be referred to as air entrance means. The valve body 23 is also provided with an air exit or exit means 34. Entrances 32, chamber 26, and air exit 34, therefore, define a fluid passage from the distributing chamber 22 to the air conduit 19 leading to the tool cylinder 28. This passage may be followed by the arrows in Figure 1. Pins 41 interlock the valve body 23 relative to the tool body 10 to maintain alignment between air exit 34 and conduit 19.

The operation of the distributing valve 21 is set forth in the Figures 1 and 2. It does not matter in what position the piston 16 happens to be as motive fluid is first applied to the tool, but for the purposes of illustration, let it be assumed that the piston 16 is in the position illustrated in the Figure 1. As the air is applied through the air line 15, the distributing chamber 22 is filled and air begins to enter through both the air entrances 31 and 32. The ring valve 35 will not stop air from entering both entrances during the initial starting moment. However, air attempting to pass through the air conduits 19 to exhaust 20 will be blocked by the piston 16. On the other hand, air exhausting from the valve chamber 26 through the air exit 33 will be vented directly to atmosphere through the cylinder 28 and the exhaust 20. Therefore, a differential of air pressure is immediately built up between the two exits 33 and 34 from the valve 21 and the air will attempt to flow out of the air exit 33. Thus, a differential of pressure is created between the flat surface 37 and the flat surface 36 on the ring valve 35. The ring valve 35 is consequently drawn tightly against the flat surface 29 of the cap 25 and blocks off both the air entrance 31 and the air exit 33. Therefore, the air can only travel through the air passage comprising the air entrance 32, the chamber 26, and the air exit 34 to the air conduits 19 as illustrated by the small arrows following the air path in the Figure 1. The compressed motive fluid as thus directed through the air conduit 19 will, therefore, create a differential of air pressure with respect to the piston 16 and force the piston 16 toward the end of the tool cylinder 28 defined by the internal bore 27 of the valve 21.

The piston 16 fits closely to the tool cylinder 28 along a portion of the length of the piston and, therefore, provides an upper corner 39 and a lower corner 40. As the upper corner 39 of the piston 16 passes the upper edge of the air

exhaust 20, the air pressure in that portion of the cylinder 28 is compressed to a small extent, but more important, is no longer freely exhausted to atmosphere. Further, as the corner 40 of the piston 16 passes the lower edge of the air exhaust 20, the air conduits 19 are vented to atmosphere; therefore, the pressure resisting exhaust through the air conduits 19 is greatly reduced. Because of the reduction in resistance to the air flow through air conduit 19, and because of the concurrent increase of resistance to air flow from the cylinder 28 at the valve end, the differential of pressure previously existing in the position illustrated in Figure 1 will be reversed and consequently, the ring valve 35 will be quickly drawn tightly against the flat wall 30 at the bottom of the valve chamber 26. Thus, the flow of air through the passage defined by the air entrance 32, the chamber 26, and the air exit 34 will be blocked and the air will be directed through the air entrance 31 in the cap 25, the chamber 26, and out through air exit 33 into the adjacent end of the tool cylinder 28. The consequent differential of air pressure upon the piston 16 will drive the piston 16 down toward the tool bit 17 with great force.

As the upper corner 39 closes the exhaust 20 in the upward movement of the piston 16, or as the lower corner 40 closes the exhaust 20 in the downward movement of the piston 16, the motive fluid trapped in the respective ends of the tool cylinder 28 will be compressed considerably and, therefore, help to change over the pressure differential within the chamber 26 acting upon the ring valve 35, but the slight compression thus created is small in effecting the change as compared to the sudden venting of the air exits 33 and 34 to atmosphere.

In the Figure 11, the ring valve 35 is illustrated as having a rectangular cross-sectional area with a surface dimension to adequately cover the inlets and outlets of the valve 21, but being free to move rapidly into contact with one or the other of the flat walls 29 and 30. It has been found, however, that the use of improper lubricants in the air stream will sometimes deposit a film on the flat surfaces 29 and 30 which will tend to cause flat surfaces 36 and 37 to adhere tightly to the flat surfaces 29 and 30. This resistance to separation is more than mere tackiness of the lubricant, but is the same principle as illustrated by the adherence of two perfectly flat ground surfaces clinging together by air pressure differential. Therefore, it has been found that the ring valve 35 may preferably be warped out of a perfect plane form a slight amount in order to present a surface which does not exactly match the flat surfaces 29 and 30. However, the ring valve 35 is resilient and, therefore, may be drawn into perfect sealing contact with surfaces 29 and 30 by the pressure differential operating the valve. Thus, when the pressure differential reverses as previously described, the momentary equalization of air pressure during the transition of the air pressure will allow the resiliency of the ring valve 35 to snap to a warped shape and break the natural air seal which might otherwise cause the ring valve 35 to cling and delay the rapid reversal of air direction.

Although the invention has been described in its preferred form with a certain degree of particularity, it is understood that the present disclosure of the preferred form has been made only by way of example and that numerous changes

in the details of construction and the combination and arrangement of parts may be resorted to without departing from the spirit and the scope of the invention as hereinafter claimed.

What is claimed is:

1. An air tool comprising, a tool body having a cylindrical bore, said cylindrical bore having a first and a second end, and an intermediate portion between the ends, said tool body having an opening through the said intermediate portion of the bore providing an exhaust port, an annular valve body having an annular groove therein with a flat wall bottom, an annular valve cap having a flat wall surface, the valve cap and valve body comprising a valve cage, a cap member threadably engaged on said first end of the tool body, said valve body and valve cap clamping held together and in operative position at the first end of said tool body by said cap member, said valve cage having an internal bore, said cylindrical bore of the tool body and internal bore of the valve cage comprising a tool cylinder, the groove in the valve body defining an annular valve chamber therein having the flat wall surface of the valve cap as a first flat wall of the chamber, and the flat wall bottom of the groove as a second flat wall of the chamber, said valve cap having at least an opening through said first flat wall for a first air entrance into said chamber, said valve cap having at least an opening through said first flat wall for a first air exit from said chamber, said valve body having at least an opening through said flat wall bottom for a second air entrance into said chamber, said valve body having at least an opening through said flat wall bottom for a second air exit from said chamber, an annular resilient valve ring in said annular valve chamber, said valve ring being warped untrue with respect to the flat walls of the chamber and being adapted to be flattened by fluid pressure into flat sealing contact with a selected one of said first and second flat walls of the valve chamber, an air line conduit adapted to conduct air from said second exit to said second end of the cylinder, said first air exit opening into the first end of the tool cylinder, and a free piston in said tool cylinder providing a movable cylinder division whereby air may be alternately exhausted from one end of the cylinder and trapped in the other end.

2. An air tool comprising, a tool body having a cylindrical bore, said cylindrical bore having a first and a second end, and an intermediate por-

tion between the ends, a piston in said cylindrical bore providing a movable cylinder division, said tool body having an exhaust port controlled by the piston, an annular valve body having an internal bore, a cap member on said first end of the tool body, said valve body clamping held on the first end of the tool body by said cap, said annular valve body having an annular valve chamber therein, inlet passages leading from the opposite sides of the valve chamber to the ends of the tool cylinder, a supply passageway leading from a source to constantly supply pressure fluid to said valve chamber, an annular resilient valve ring in said annular valve chamber, said valve being warped untrue with respect to the sides of the valve chamber and being adapted to be flattened by fluid pressure into sealing contact with a selected side of said valve chamber and seal off the inlet passages leading therefrom.

3. An air tool comprising, a tool body having a cylindrical bore with a free piston therein, an annular valve body directing pressure fluid to the ends of said bore, said valve body having oppositely disposed walls with inlet passageways through said walls to the ends of the cylinder, a ring valve plate in said valve body, said ring valve plate free to reciprocate between the oppositely disposed valve walls and alternately block passage of fluid through the inlet passageways in the walls, said ring valve plate operating in response to change in relative back pressure against exhaust from said valve and being warped untrue with respect to the oppositely disposed walls of the valve but resilient to conform to the walls by air pressure differential.
